UNITED STATES PATENT OFFICE.

JOSEPH L. WRIGHT, OF CLEVELAND, OHIO, ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,221,262.

Specification of Letters Patent.

Patented Apr. 3, 1917.

Application filed October 31, 1914. Serial No. 869,670.

To all whom it may concern:

Be it known that I, JOSEPH L. WRIGHT, a citizen of the United States, residing at Cleveland, in the county of Cuyahoga and 5 State of Ohio, have invented certain new and useful Improvements in Telephone-Exchange Systems, of which the following is a specification.

My invention relates to telephone exchange systems employing automatic switching mechanism for interconnecting subscribers' lines and is applicable to said systems whether of the full automatic or semi-automatic types.

15 The manner in which the automatic switching mechanism is controlled allows what are termed two-wire or metallic circuits to be used. In systems employing such circuits it has been customary to employ a combination of slow and quick acting relays. These relays are responsive to current changes in the metallic circuits and control the automatic switching mechanism for effecting connection between subscribers' lines.

20 25 With my invention no slow acting relays or retarded devices are used. The current impulses for controlling the automatic switching mechanism are alternating in character. These impulses are transmitted

30 by means of an alternating current device so arranged to allow impulses of different frequencies to be transmitted for directing the action of the automatic switching mechanism.

35 The automatic switching mechanism is provided with receiving devices responsive to the impulses transmitted and in acting control the automatic switching mechanism.

40 For purpose of illustration I have shown selector and connector switches of the type shown in Patent No. 815,321 to Keith and Erickson, March 13, 1906, and Patent No. 815,176 to Keith and Erickson, March 13, 1906.

45 My invention is illustrated in the accompanying drawings wherein:

Figure 1 shows a subscriber's line equipment and a first selector circuit.

Fig. 2 shows a connector circuit.

50 Fig. 3 shows a form of dial to be used with the signal device.

Referring to Fig. 1, the subscriber's station at AA is provided with apparatus usual in common battery systems, and in addition

is provided with an alternating current 55 transmitting device 100 shown in the form of a standard type hand generator. In order to cause the proper number of impulses to be transmitted to direct the movement of the automatic switches the dial or handle 60 is moved around to transmit the proper number of impulses. In case five impulses are to be transmitted the dial is moved so as to cause five impulses to be transmitted. After the predetermined impulses are transmitted 65 the dial or handle is rapidly revolved to cause a series of alternations of high frequency to be transmitted to the automatic switches.

The number of directive impulses are determined by placing the finger in the proper opening or window and pulling the dial around until the stop is engaged. The numbers are back of the openings and do not move with the dial. The movement of the 75 dial can be retarded in any well known manner so that extra care need not be taken when operating. It is only necessary that the directive impulses are of a frequency low enough so as not to operate the high frequency relays or devices associated with the 80 automatic switches.

The directive or low frequency impulses correspond to the so-called vertical impulses in the well known Strowger system, while 85 the high frequency impulses correspond to the rotary impulses. The low frequency impulses for predeterminedly operating the automatic switches cause the operation of a tuned polarized relay B. The operation of 90 this relay in turn completes the circuit of the vertical magnet causing the first selector switch J to step vertically.

The high frequency impulses or alternations causing the operation of a polarized relay C tuned to respond to these frequencies but not to the low frequency current. This relay serves to cause the shifting of the switch circuit in certain order.

In order to transmit the impulses the receiver is removed from the hook and then the impulse device operated. This device in operating closes the contact springs 101 and 103 but breaks the contact springs 102 and 103, the effect being that the generator 105 or impulse device is connected across the tip and sleeve conductors before the telephone set is disconnected therefrom.

Referring to Fig. 2, the connector switch is shown at W. The low frequency polarized relay L in operating causes the impulses to be transmitted to the vertical and 5 rotary magnets. The operation of the high frequency polarized relay M changes the circuit conditions and allows the various magnets and other circuits to be shifted in a certain order.

10 In connection with the switch W I have provided an extra side switch arm Z for the purpose of connecting the ringing relay R at the proper time. Relay K remains energized over the line of the calling subscriber 15 while the receiver is removed or while the impulse device is being operated.

The operation of the system is as follows: The subscriber at station AA desiring to call another subscriber first removes his receiver. The removal of the receiver causes 20 the energization of relay A. The operation of this relay partially completes the circuit of the vertical magnet F so that it can be controlled by the operation of relay B and 25 also grounds the test contacts which appear in its group of connector switches. The subscriber in operating the signaling device 100 causes the first set of impulses to be transmitted and to operate relay B. The operation 30 of this relay completes the circuit of the vertical magnet F by the following path: ground, contacts of relay B, 9, contacts of relay A, 10, contacts of relay D, 11, winding of magnet F to battery BB. The operation 35 of the magnet F causes the switch J to step vertically and bring the wipers 25, 26 and 27 in line with the proper row of contacts. After the first set of directive impulses have 40 been transmitted the high frequency impulses are transmitted by the device 100, thereby causing the operation of relay C. The operation of this relay completes the circuit of the private relay D. The operation 45 of relay D causes the side switches to step to the second position, thereby connecting the winding of relay D in series with the winding of the trunk release relay E. While these windings are in series relay D is operated but relay E, as is customary, is 50 so adjusted as not to operate at this time. These relays will remain in series and relay D energized until the test wiper 27 engages an idle contact or one free from ground. As soon as such a contact is found then relay 55 D becomes deenergized and the side switches step to the third position. In taking this third position the trunk conductors are extended to the wipers 25 and 26 respectively and ground connected directly to the winding of relay E. Ground being connected in this manner renders the test contact engaged by the wiper 27 busy against other calls.

The operation of the side switch arm 300 connects ground to the test contact 19 after 60 relay A becomes disconnected by the side

switches moving to the third position. Ground maintained in this manner renders the calling line busy against other calls and also operates relay I.

The calling subscriber is now connected to an idle connector such as shown in Fig. 2. As soon as such a connector is engaged then 70 relay K becomes energized over the calling subscriber's line circuit while relay O becomes energized in series with the winding 75 of the relay E and the resistance coil 43. The winding of this coil is of comparatively high resistance so as to prevent the operation of relay E. Relay O, however, is so adjusted that it will operate in series with relay E and the resistance 80 43.

The subscriber at station AA now operates the transmitting device and causes the second series of directive impulses to be transmitted to the connector switch, thereby 85 operating the polarized relay L. The operation of this relay completes the circuit of the vertical magnet T by the following path: ground, contacts of relay L, 56, contacts of relay N, 57, side switch, 58, winding of 90 magnet T to battery BB. The operation of the magnet T causes the switch W to step vertically and bring its wipers 35, 45 and 50 in line with the proper row of contacts.

After the second series of impulses have 95 been transmitted a series of high frequency impulses are then transmitted, thereby operating relay M. The operation of this relay completes the circuit of the private relay N causing the side switches to step to their second position. The calling subscriber then causes the third set of directive impulses to be transmitted thereby operating relay L. The operation of this relay at this time completes the circuit of the rotary magnet U as the vertical magnet T was disconnected when the side switches moved to the second position. The third series of impulses causes the switch W to bring the wipers to rest on contacts associated with the called-for line. 100

A series of high frequency impulses are next transmitted at the calling station thereby causing the operation of relay M. The operation of this relay again completes the circuit of the private relay N. The operation of relay N at this time connects the test relay S to the test wiper 50 by the following path: battery BB, winding of relay S, 65, contacts of relay N, 64, side switch, 63, test wiper 50. In case the called-for line 110 is busy, ground will be connected to the test contact thereby operating relay S. The operation of this relay completes the circuit of the release magnet V causing the restoration of the switch W. This relay S remains 115 locked to ground through the contacts of relay O. The operation of relay S connects a suitable busy tone test or signal to the trunk conductor, thus notifying the calling subscriber that the called-for line is busy. 120

130

In case, however, the called-for line is not busy relay S will not be affected and the switch wipers will remain in engagement with the contacts of the called-for line and the side switches will step to the third position, thereby connecting the trunk conductors to the wipers 35 and 45 respectively.

The operation of the side switches also causes ground to be connected directly to the test wiper 50, thus rendering the called line busy against other calls.

At the final step of the side switch Z the circuit of the ringing relay R is completed as follows: ground, commutator Y, winding of the relay R, 71, contacts of relay X, 70, Z to battery BB. Relay R is operated intermittently by means of the commutator Y and applies generator current to the called line.

In case, however, the called subscriber does not respond then the calling subscriber controls the release of the connector switch as well as the release of the first selector switch. In this event the release of the connector switch is effected by the action of relay K which in restoring completes the circuit of the release magnet V by the following path: ground, cam springs 55, 46, contacts of relay K, 47, contacts of relay X, 48, winding of magnet V to battery BB.

While I have shown the signaling or transmitting device in the form of a hand generator, the speed being controlled by the subscriber, it of course follows that this device can be so constructed that the speed is automatically regulated.

In automatic systems it is common practice to have the dial or signaling device transmit the impulses in restoring, the speed in restoring being controlled by suitable gears and governor.

In connection with Fig. 1 I have shown an impedance or resistance coil 105 bridged across the conductors connected to contacts 102 and 103. This coil is simply used as an alternative and can be omitted if desired. Its function is merely to allow the telephone set at the subscriber's instrument to remain in circuit with the line in series with the winding of the coil 105. The impedance of this coil would be such that the current generated by the device 100 would not be shunted and prevent the operation of the tuned relays.

While I have shown but one impulse device or generator for transmitting currents of different frequencies it of course follows that one generator can be applied for each frequency.

Having thus described my invention what I desire to secure by Letters Patent is:

1. In a telephone exchange system, subscribers' lines, connective means for the lines, means at the subscribers' stations to produce alternating current impulses of relatively low frequency for operating said connective means, additional means at the subscribers' stations to produce alternating current impulses of relatively high frequency, to produce changes in the circuits of the connective means, substantially as set forth.

2. In a telephone exchange system, the combination with an automatic switch, of an alternating current signaling device for controlling the operation of said switch, two conductors extending from said device to said switch normally closed during the op-

10 15 20 25 30 35 40 45 50 55 60 65 70 75 80 85 90 95 100 105 110 115 120 125 130

the wiper 27 disengages the test contact then relay O becomes deenergized and the intermittent shunt is removed from the coil 43.

It will be noted that when the called subscriber answers he retains control of the connector switch and causes its release when replacing his receiver.

In case, however, the called subscriber does not respond then the calling subscriber controls the release of the connector switch as well as the release of the first selector switch.

In this event the release of the connector switch is effected by the action of relay K which in restoring completes the circuit of the release magnet V by the following path: ground, cam springs 55, 46, contacts of relay K, 47, contacts of relay X, 48, winding of magnet V to battery BB.

While I have shown the signaling or transmitting device in the form of a hand generator, the speed being controlled by the subscriber, it of course follows that this device can be so constructed that the speed is automatically regulated.

In automatic systems it is common practice to have the dial or signaling device transmit the impulses in restoring, the speed in restoring being controlled by suitable gears and governor.

In connection with Fig. 1 I have shown an impedance or resistance coil 105 bridged across the conductors connected to contacts 102 and 103. This coil is simply used as an alternative and can be omitted if desired. Its function is merely to allow the telephone set at the subscriber's instrument to remain in circuit with the line in series with the winding of the coil 105. The impedance of this coil would be such that the current generated by the device 100 would not be shunted and prevent the operation of the tuned relays.

While I have shown but one impulse device or generator for transmitting currents of different frequencies it of course follows that one generator can be applied for each frequency.

Having thus described my invention what I desire to secure by Letters Patent is:

1. In a telephone exchange system, subscribers' lines, connective means for the lines, means at the subscribers' stations to produce alternating current impulses of relatively low frequency for operating said connective means, additional means at the subscribers' stations to produce alternating current impulses of relatively high frequency, to produce changes in the circuits of the connective means, substantially as set forth.

2. In a telephone exchange system, the combination with an automatic switch, of an alternating current signaling device for controlling the operation of said switch, two conductors extending from said device to said switch normally closed during the op-

eration of the signaling device and during the operation of said switch, substantially as set forth.

3. In a telephone exchange system, the combination with an automatic switch, of two conductors extending to said switch having an associated alternating current signaling device, means associated with said switch and responsive to the operation of said signaling device for controlling the action of said switch, said conductors being closed during the operation of said signaling device, substantially as set forth. 4. In a telephone exchange system, automatic switching mechanism and metallic line circuits, of devices associated with said automatic switching mechanism adapted to respond to alternating currents of different frequencies, means at the subscribers' stations to operate said devices over said line circuits to determine the positions to be assumed by said automatic switching mechanism, substantially as set forth. 5. In a telephone exchange system, the combination with an automatic switch, of an alternating current signaling device for controlling the operation of said switch, two conductors extending from said device to said switch normally closed during the operation of the signaling device and during the operation of the said switch, releasing means associated with said switch rendered operable when said conductors are opened, substantially as set forth. 6. In a telephone exchange system, the combination with an automatic switch, of two conductors extending to said switch, or an alternating current signaling device for controlling said switch over said conductors while said conductors are closed, releasing means for said switch controlled by the opening of said conductors, substantially as set forth. 7. In a telephone exchange system, the combination with a traveling automatic switch, actuating means for said switch responsive to alternating current impulses, releasing means for said switch, said releasing means being unresponsive to said impulses, substantially as set forth. 8. In a telephone exchange system, the combination with calling and called subscribers' lines, of traveling automatic switches for interconnecting said lines, means associated with each of said automatic switches and responsive to alternating currents of different frequencies for actuating said automatic switches to interconnect said lines, of releasing means associated with said automatic switches unresponsive to said alternating currents for releasing said automatic switches, substantially as set forth. 9. The combination with an automatic switch, actuating means for said switch, shifting means for said switch, releasing means for said switch, a control circuit, additional individual means in said circuit associated with each of said means and directly responsive to current changes over said circuit for controlling said switch, substantially as set forth. 10. In a telephone exchange system, the combination with an automatic switch, an alternating current signal device, of a relay associated with said switch and responsive to alternating currents of a low frequency for directly operating said switch, of a second relay responsive to currents of higher frequency for controlling the shifting means of said switch.

In testimony whereof I affix my signature in presence of two witnesses.

JOSEPH L. WRIGHT.
